UNITED STATES PATENT OFFICE.

MAX KATZ, OF PROVIDENCE, RHODE ISLAND.

DESIGN FOR A CLOCK CASE.

Application filed July 1, 1924. Serial No. 10,021. Term of patent 3½ years.

To all whom it may concern:

Be it known that I, MAX KATZ, a citizen of Russia, and a resident of Providence, in the county of Providence and State of Rhode Island, have invented a new, original, and ornamental design for a Clock Case, of which the following is a specification.

Reference is to be had to the accompanying drawing in which the figure is a front perspective view of a clock case, showing my new design.

I claim—

The ornamental design for a clock case as shown.

MAX KATZ.
